UNITED STATES PATENT OFFICE.

ELMER W. BORGER, OF PALMERTON, PENNSYLVANIA.

ADJUSTABLE FOLDING STAND.

Application filed July 17, 1922. Serial No. 575,700.

To all whom it may concern:

Be it known that I, ELMER W. BORGER, a citizen of the United States, residing at Palmerston, in the county of Carbon and State 5 of Pennsylvania, have invented new and useful Improvements in Adjustable Folding Stands, of which the following is a specification.

This invention relates to adjustable folding stands and more particularly to devices of this character which can be provided with a sewing machine and so adjusted as to be conveniently used to sew in windows or make repairs to vehicle curtains or the like 15 without removing the curtain from the vehicles or which may also be used as an ironing board and when not in use, collapsibly folded and conveniently stored.

An object of my invention is, to provide 20 means in a device of the character described which will permit of the convenient sewing of any part of the curtains of an automobile or other vehicle for installation of windows therein or repair thereto without removing 25 the curtains from the vehicle and which may be also used as a convenient ironing board adjustable to any suitable height and which may be collapsibly folded to permit its storage.

Referring to the drawings in which like 30 numerals of reference indicate corresponding parts—

Fig. 1 is a side elevation, with one side removed showing some parts in vertical section taken on line 1—1 of Figure 2, looking in the direction of the arrow.

Fig. 2 is an end elevation of my device with the parts assembled as shown in Fig. 1.

Fig. 3 is a side elevation with a part 40 broken away for purposes of clearness, showing my device equipped with a sewing machine and with an extended arm thereof in elevated position and in dotted lines with the arm in position for use as an ironing board.

Fig. 4 is a vertical, longitudinal sectional view taken on line 4—4 of Fig. 2 showing a ball-bearing swivel joint provided in my device.

Fig. 5 is a vertical transverse sectional view, taken substantially on line 5—5 of Fig. 1 showing a ball-bearing swivel joint provided in my device.

Referring more particularly to the drawings my invention consists of a supporting frame-work comprised of a pair of standards

2 and 3 and a pair of standards 4 and 5 which are mounted and assembled on a common pivot 6 at their top ends. The standards 2 and 3 are joined at their lower ends by transverse brace 7 and the standards 4 and 5 are likewise joined at their lower ends by the transverse brace member 8. The standards 2 and 3 and the standards 4 and 5 are each provided with similar longitudinal channels 9 from one side of which in each standard there extends a series of insets or slots 10. The channels 9 are adapted to receive and permit to travel longitudinally therein transverse connecting slide bars on pivot members 11 and 12, the bar 11 joining the standards 2 and 3 while the bar 12 joins the standards 4 and 5 and operate slidably in the respective channels and slots in these standards. Between the bars 11 and 12 and 75 pivotally mounted thereon is a framework composed of transverse bars 13 and 14 braced together by cross braces 15 and 16. Mounted also on the transverse bar 12 are the substantially vertical pivotal brace members 17 and 18 connecting at their lower ends with the member 12 at their upper ends engaging the pivot pins 19 on the opposite edges of the swinging arm or supporting member 20 and thereby holding the supporting member, which is pivotally mounted on one of its ends to the connecting pivot member 6, in operative elevated position. The members 17 and 18 are joined by cross bars 21 and 22 which act as a strengthening 80 framework between these bars and also cause them to operate together; which is likewise the function of the bars 15 and 16 on the bars 13 and 14. The member 20 is in the nature of a base or table and being 85 hinged or pivoted on the pivot member 6 is adaptable to angular vertical elevation on said pivot to any desired degree. This is accomplished by causing the bar 12 to be moved up or down the length of the slot 9 100 in the standards 4 and 5 and when the arm 20 has reached the desired position of elevation the bar 12 is dropped or caused to be seated in one of the slots 10 in the channel 9, and thereby supports and locks the arm 105 20 in such position. It will be seen from this that the arm 20 may be elevated or lowered at any vertical angle as required upon the pivot 6. A further adjustment of this arm 20 can be accomplished by a similar movement of the bar 11 in the slot 9 provided in the standards 2 and 3 so that the standards

2 and 3 may by moving the bar 11 downwardly or upwardly in the channel 9, be drawn closer to or distended from the standards 4 and 5 and will, as their position is 5 changed in reference to standards 4 and 5 result in changing the angular position of the arm 20 for elevation or depression.

Upon the outer end of the arm 20 I have made provisions for the mounting of a movable and detachable extension 23 upon which I mount in any usual way a sewing machine 24 which can be operated by hand and which is in fixed relation to the table or extension 23. The table 23 is in rotatable pivotal engagement with the arm 20, by means of a pivot mechanism to be described hereinafter. It is also provided with a longitudinal slot 25 which adapts the table 23 to longitudinal movement on its pivot or in 10 reference to the arm 20. The pivot means mounting the table 23 upon the arm 20 consists of a pivot pin or axis 26 provided on one end with a locking thumb nut 27, adapted to lock the table 23 in any position 15 of adjustment on the arm 20. It is also provided with a socket 28 carrying balls 29 forming a bearing for the member 30 carried by the table 23 so that turning movement of the table 23 upon its pivot 26 will 20 result from very slight force. This feature of my device is of essential importance, because in the operation of sewing for repair or for the installation of a window in the curtain of an automobile or other vehicle, it 25 is desired that, as the sewing operation takes place, the machine will by pull exerted by its needle, properly position itself for the seam being made and will therefore when once started need no guiding by the operator al- 30 though the part being sewed will of course require direction of the operator. In order to provide additional locking of the table 23 against rotation on its pivot I mount pivoted stops 31 on opposite edges of the 35 arm 20 near its outer end, so that they may be turned on their pivots and engage the opposite edges of the table 23 and restrain it against lateral movement when it is not desired that it turn on its pivot, as for in- 40 stance when a straight seam is being sewed.

By the provision of the supported arm 20 with such an adjustability as is possible in the device as constructed by me I can quickly sew any portions of vehicle curtains or 45 can insert a window therein and make any other repairs to the curtain or top requiring a sewing operation, without the removal of the top or curtain.

Further my device is portable and can 50 therefore be quickly brought to the vehicle upon which the repair is to be made, without any unusual labor, owing to the fact that the device is of simple and light construction although durable and well braced to 55 assure steadiness of position while being

operated. It is also a very useful apparatus in a motor or motor top repair shop, especially because of its portability and its adaptability to angular adjustment of the arm 20 for varying heights.

Although I have specified my device to be especially adapted for use in connection with sewing of automobile tops or curtains yet it may be conveniently used in any factory where sewing operations are performed; and in this connection it will be noted that in such factories there is frequent use of an ironing board upon which garments or other sewed articles may be pressed, and for this use my device is well adapted when the table 23 carrying the machine 24 is removed from the arm 20.

Another desirable feature is that when not in use my apparatus may be closely folded together in a compact form and conveniently stored in a small space.

This folding operation can take place by removing the bars 11 and 12 from their position in the notches 10 in the channels 9 on the standards 2, 3, 4 and 5 and moving them to the ends of said channels 9 in opposite directions and closing the standards 2 and 3, 4 and 5 together thus drawing the arm 20 down into a collapsed position between the standards 4 and 5, on its pivot 6.

It will be seen from the foregoing that I have provided a novel means to perform the sewing operations above referred to and that these means are of simple construction, light and durable and of convenient adjustability for the purposes set forth and which may have advantages and results not herein specified.

Although I have shown and described one embodiment of my invention I do not wish to be limited thereby, for it is obvious that modifications may be made in the construction, operation and organization of parts without departing from the scope of my invention.

Having thus described my invention what I claim as new and desire to secure by Letters Patent is—

1. In a device of the character described, the combination of pivotally connected, spaced supporting standards, having notched channel portions longitudinally disposed therein, a supporting arm pivotally mounted at one end between the upper ends of said standards, transverse pivot members carried between said standards and adapted to seat in said channel and notched portions, substantially horizontally disposed transverse bars mounted on said pivot members and co-operating therewith, substantially vertically disposed brace members mounted on one of said pivot members at one end and pivotally supporting said pivoted arm at their opposite end, said pivot members being adapted to longitudinal adjustment in said channel

and notched portions and thereby effect vertical adjustment of said arm member on its pivot.

2. In a device of the character described, 5 the combination of pivotally connected spaced supporting standards, having notched channel portions longitudinally disposed therein, a supporting arm pivotally mounted at one end between the upper ends of said 10 standards, an auxiliary table or extension, detachably and pivotally mounted on the free end of said arm and slideable longitudinally thereon and adapted to oscillate in a plane substantially parallel to the plane of 15 the pivoted arm, transverse pivot members carried between said standards and adapted to seat in said channel and notched portions, substantially horizontally disposed transverse bars mounted on said pivot members 20 and co-operating therewith, substantially vertically disposed brace members mounted on one of said pivot members at one end and pivotally supporting said pivoted arm at their opposite ends, said pivot members being 25 adapted to longitudinal adjustment in said channel and notched portions and thereby effect vertical adjustment of elevation or depression of said arm member on its pivot,
3. In a device of the character described, 30 the combination of pivotally connected, spaced supporting standards having notched channel portions longitudinally disposed therein, a supporting arm pivotally mounted at one end between the upper ends of said 35 standards, an auxiliary table or extension detachably and pivotally mounted on the free end of said arm and slideable longitudinally thereon and adapted to oscillate in a plane substantially parallel to the plane of the pivoted arm, means to lock said auxiliary table against lateral oscillation or longitudinal movement on said arm, transverse pivot members carried between said standards and adapted to seat and longitudinally move in 40 said channel and notched portions, substantially horizontally disposed transverse bars mounted on said pivot members co-operating therewith, substantially vertically disposed brace members mounted on 45 one of said pivot members at one end and pivotally supporting said pivoted arm at their opposite ends, said pivot members being adapted to longitudinal adjustment in said channel and notched portions and thereby, 50 by means of said vertically disposed brace members, effect vertical adjustment of ele-

vation or depression of said arm member on its pivot.

4. In a device of the character described, 60 the combination of pivotally connected, spaced supporting standards having notched channel portions longitudinally disposed therein, a supporting arm pivotally mounted at one end between the upper end of said standards, transverse pivot members carried between said standards and adapted to seat and longitudinally move in said channel and notched portions, substantially horizontally disposed transverse bars mounted on said pivot members and co-operating therewith, 65 substantially vertically disposed brace members mounted on one of said pivot members at one end and pivotally supporting said arm at their opposite ends, said pivot members being adapted to longitudinally slide in 70 said channel and notched portions and thereby permit a collapsible folding together of said standards and brace members and pivoted arm member in compact form and close 75 relation to each other.

5. In a device of the character described, 80 the combination of pivotally connected, spaced supporting standards, having notched channel portions longitudinally disposed therein, a supporting arm pivotally mounted 85 on one end between the ends of said standards, an auxiliary table or extension detachably longitudinally slidably and pivotally mounted on the free end of said arm adapted to oscillate in a plane substantially 90 parallel to the plane of the pivoted arm, a sewing machine mounted on said auxiliary table and adapted, in the operation of sewing, to move said table longitudinally or laterally upon its pivot, transverse pivot members carried between said standards and adapted to seat and longitudinally move in 95 said channel and notched portions, substantially horizontally disposed transverse bars mounted on said pivot members and co-operating therewith, substantially vertically disposed brace members mounted on one of said pivot members at one end and pivotally supporting said pivoted arm at their opposite end, said pivot members being adapted 100 to longitudinal adjustment in said channel and notched portion and thereby effect vertical adjustment of elevation or depression of said arm member, and parts carried thereon, upon its pivot.

In testimony whereof I affix my signature.
ELMER W. BORGER.
